UNITED STATES PATENT OFFICE.

MORRIS W. POOL, OF NEW YORK, N. Y., ASSIGNOR TO UNION TYPEWRITER COMPANY OF NEW JERSEY, OF JERSEY CITY, NEW JERSEY, A CORPORATION OF NEW JERSEY.

TYPE-WRITING MACHINE.

1,033,268.

Specification of Letters Patent. Patented July 23, 1912.

Application filed February 29, 1912. Serial No. 680,588.

To all whom it may concern:

Be it known that I, MORRIS W. POOL, citizen of the United States, and resident of the borough of Brooklyn, city of New York, 5 in the county of Kings and State of New York, have invented certain new and useful Improvements in Type-Writing Machines, of which the following is a specification.

My invention relates particularly to tally strip devices for typewriting machines and 10 its general object is to provide improved devices of the class specified.

To the above and other ends my invention consists in the features of construction, 15 combinations of devices and arrangements of parts hereinafter described and particularly pointed out in the claims.

In carrying out my invention I arrange 20 the tally strip to extend around the right-hand end portion of the platen from the delivery roll holder to a receiving roll holder, the roll holders being mounted on a frame which is secured to the platen carrier. The 25 bill sheet is adapted to be superposed on the tally strip, the writing being transferred to the latter from a carbon strip which is preferably wound up with the tally strip. The tally strip is fed by devices which operate 30 on the receiving roll holder to turn the same and wind the tally strip thereon, these devices being separate from the regular line spacing devices of the machine. For the 35 purpose of insuring that the tally shall be line spaced the tally feeding devices are associated with line locking devices which are set to operate as the tally strip enters the printing field of the types. In order to unlock the line locking devices and permit the tally strip to be printed upon, it is necessary 40 to press a key which not only unlocks the line lock but also spaces the tally strip.

The gist of the invention lies in preventing the tally strip from being printed upon until after it has been fed or line spaced to 45 move the previously printed item past the printing line.

In the accompanying drawings which illustrate one form of my invention,

Figure 1 is a central vertical sectional view taken fore and aft of a Monarch type-writing machine to which my invention is

shown as applied, parts being omitted and parts broken away. Fig. 2 is a fragmentary front elevation of the platen and carriage of the machine and associate parts. Figs. 3, 4 55 and 5 are fragmentary operating views taken in front elevation. Fig. 6 is a perspective view of part of the tally mechanism.

In the drawings the frame of the machine 60 comprises a base 1, posts 2 and a top plate 3. Key levers 4 are connected with sub-levers 5 which in turn are connected by links 6 with type bars 7 adapted to strike the front face of a platen 8 mounted in a traveling platen carrier or carriage comprising end bars 9 65 and a connecting slide bar 10, the latter being grooved to co-operate with anti-friction balls 11 which also coact with fixed guide rails 12. The usual spring drum by which the traveling carriage is drawn leftward is 70 omitted from the drawings. The carriage feeding devices may be of ordinary construction comprising a toothed escapement wheel 13 with which co-operate dogs 14 and 15 mounted on a pivoted dog rocker 16 75 which is connected by a link 17 with the central rearwardly extending arm of a universal bar frame 18 which carries a universal bar 19 underlying the key levers. Associated with the platen are the usual paper 80 feeding devices comprising feed rolls 20 and 21 which extend along the platen but stop short of the tally strip at the right-hand end of the platen. The platen is rotatable for line spacing purposes by the usual line 85 spacing devices comprising a ratchet wheel 22 connected to the left-hand end of the platen and operated upon by a pawl 23 controlled by a lever or finger piece 24.

The tally roll holders may be mounted on 90 a frame or support comprising end plates 25 and 26 connected by a tie rod 27. Said frame may be detachably secured to the platen carriage at the right-hand end thereof and for this purpose the plates 25 and 26 95 are provided with hubs 28 which fit over and are detachably secured to the usual paper finger rod 29 which extends lengthwise above the platen and is mounted on the end bars 9. The plate 25 is provided with an 100 extension 30 which is bifurcated at its end to fit over the usual release rock shaft 31.

Said extension has pivoted to it a hook 32 which coöperates with the rod 31 as shown in Fig. 1 to assist in keeping the extension 30 in place, the extension 30 acting as a brace for the supporting frame. Detachably journaled on said supporting frame are tally roll holders 33 and 34 of any suitable construction, said roll holders being mounted on shafts 35 and 36 which bear in the end plates 25 and 26. The left-hand ends of the shafts are formed with grooves 37 which are outside the plate 26 and receive latches 38 pivoted at 39 to said plate. When the latches are lifted the shafts may be withdrawn and the roll holders removed. These roll holders, as shown in Fig. 1, are arranged above the platen, the roll holder 33 or delivery roll holder in rear of the other. The tally strip 40 is wound on the roll holder 33 and is led downward from the rear side thereof and extends around the platen and upward at the front side thereof, being wound on the receiving roll holder 34.

Associated with the roll holder 34 are tally feeding or line spacing devices which are arranged outside the end plate 25 and comprise a pinion 41 having a hub 42 which is pinned to the outer end of the shaft 36. Said pinion meshes with a pinion 43 pivoted at 44 to the end plate 25. Rigid with the pinion 43 is a ratchet wheel 45 with which coöperates a pawl 46 pivoted at 47 to the forward arm 48 of a tally feeding lever which terminates at the front in a finger piece or key 49 and is provided with a hub 50 which bears on the rod 29 and is confined between the plate 25 and a collar 51 fixed to said rod. A spring 52 maintains the pawl 46 constantly engaged with the ratchet wheel 45; also the arm 48 is normally maintained against a stop pin 53 by a draw spring 54. The rear arm 55 of the tally feeding lever is rigid with the hub 50 and curves downwardly and rearwardly therefrom, being bent or off-set laterally leftward at its lower end as indicated at 56, the offset terminating in a downward extension 57 to which is pivoted at 58 a finger or trip 59, said trip depending from its pivot and having an extension 60 above the pivot which is adapted to coöperate with the right-hand face of the extension 57 so that as the trip moves toward the lift it will be rigid with the extension whenever an obstruction is encountered by its lower end below the pivot. The line locking device or trip 59 on the carriage is adapted to coöperate with a line locking device on the frame of the machine. The latter device is in the present instance a normally upright member or stop 61 pivoted at 62 to the usual line locking bail 63 of the Monarch machine, said bail extending lengthwise of and in front of the lower trackway

12 and being pivoted at its ends at 64 to the ends of said trackway. A spring 65 maintains the bail normally in the position shown in Figs. 1 and 2. The pivoted stop member 61 is adapted to coöperate with stop pins 66 and 67 on the bail, a spring 68 normally maintaining the member 61 against the stop 66, as shown in Fig. 2.

The bail 63 coöperates with a line locking member 69 through a pin 70 which projects rearward from the bail and underlies a tail piece 71 of the member 69, which member is pivoted at 72 to the lower trackway 12. The member depends from its pivot and terminates at the lower end in a hook 73 which is adapted to swing under a finger 74 fixed to the link 17. Normally the parts are in the Fig. 2 position, the pin 70 which underlies the tail piece 71 maintaining the hook 73 disconnected from the finger 74. By depressing the bail 63 the pin 70 is lowered, permitting the member 69 to swing on its pivot 72, owing to the action of gravity and causing the hook 73 to engage with the finger 74. At this time the operation of the key levers 4 will be prevented, owing to the fact that the universal bar 19 will be held against depression by the link 17 which in turn will be held from being lowered by the hook 73 acting on the finger 74. Thus not only will the type bars be prevented from being swung up to the platen to print, but also the dog rocker 16 will be held from movement so that the escapement will be locked and the carriage prevented from advancing in letter space direction. The lowering of the bail and the consequent locking of the parts, as described, is brought about in the present instance by the co-action of the trip 59 with the stop 61. As will be understood from Fig. 2, these parts are so disposed and arranged that the trip will be brought into contactive engagement with the stop 61 just before the carriage has advanced far enough to the left to bring the tally strip into the printing field or opposite the printing point, the printing point being designated by the reference character *p* in Fig. 2. As shown in said Fig. 2 the parts are positioned so that writing will take place on the bill sheet 75 just to the left of the left-hand edge of the tally strip 40. In the course of the next few letter space movements of the carriage the trip 59 will engage with the right-hand edge of the stop 61 and will swing said stop leftward against the spring 68 until the stop is arrested from further swinging movement about its pivot 62 by contact with the stop pin 67. As soon as the stop 61 is thus arrested further leftward movement of the carriage will cause the trip 59, acting through the stop 61, to depress the bail 63, permitting the hook 73 to swing rightward and lock under the finger 74, as

shown in Fig. 4. This locking operation takes place just as the left-hand edge portion of the tally strip enters the printing field. As a consequence, if the operator should attempt to depress a printing key in order to print on the tally strip the actuated type being locked could not swing to the platen to print, and furthermore, since the dog rocker 16 is locked against forward 10 swinging movement, the carriage in consequence is locked against leftward advance.

In order to release the line lock the operator depresses the key 49, resulting in the turning of the tally feed lever on its pivot 15 and a lifting of the trip 59 so that the stop 61 is free from the trip and is swung back rightward by its spring 68 to contactive engagement with the stop 66. Simultaneously the pawl 46 will be moved downward 20 and will coöperate with the engaged tooth of the ratchet 45 to turn the latter. This turning movement will be transmitted to the pinion 43 and from it to the pinion 41, the latter operating to turn the receiving 25 roll 34 and wind the tally strip thereon. A stop pin 76 on the plate 25 is adapted to coöperate with the lever arm 55 to limit the swinging movement of the tally feeding lever, the parts being arranged so that when 30 the tally feeding lever is arrested by the pin 76 the tally strip will have been advanced a line space distance. When the operator releases the key 49 the tally feeding lever will be restored to normal position by the spring 35 54 and the trip 59 will swing downward to the left of the stop 61. Consequently the printing key levers 4 may now be operated to print on the work sheet 75, the impressions being simultaneously transferred 40 through a carbon or transfer sheet (not shown) to the underlying tally strip 40. When the carriage is restored toward the right the trip 59 will be brought into contact with the left-hand face of the upright stop 45 61 and yielding will turn on the pivot 58, as shown in Fig. 5, dropping down again under the force of gravity to normal position after the stop 61 has been passed. The construction is such, it will be noted, that 50 return movements of the carriage are not obstructed by the trip 59 and the stop 61.

In operation after the operator has completed the writing on one bill and has written the corresponding tally item, the completed bill is removed and a fresh bill is inserted and written. The items written on the fresh bill will all be at the left of the tally strip except the total which is to be printed on that portion of the bill which 55 overlies the tally strip. Consequently if it be attempted to move the carriage leftward far enough to position it for printing the total, the line locking stops will coöperate 60 to effect the locking of the types and the ar-

rest of the carriage and said stops can only 65 be unlocked to free the parts by an actuation of the key 49. The depression of this key of course advances the tally strip so that the previously written tally is carried past the printing point and a fresh portion of the 70 tally strip is brought into register with the printing line. Thus an effective check is provided which insures that the tally strip line spacing devices shall be actuated in desired intervals.

Although the carriage has been described as being arrested by the line locking stops prior to the actuation of the key 49, it will be understood that the operator need not wait to actuate the key until the carriage is 75 arrested and the line locked. On the contrary, it is preferable, after the items of the bill have been written, to move the carriage leftward until it is brought opposite the place where the total is to be printed. To 80 do this the carriage must be released from its escapement devices and this may readily be accomplished in known ways as by the depression of the right-hand release key 77 which is in common use on the Monarch 85 machine. In order to insure an unobstructed leftward movement of the carriage at this time the trip or line locking stop 59 must, of course, be lifted out of the path of the stop 61, this being done by depressing 90 the key 49 which operates also to feed the tally strip. It will be observed that the keys 49 and 77 are in proximity to each other and so disposed that they may be operated concurrently or contemporaneously 95 by the same hand of the operator, preferably his right hand, so that all that is needed after the bill has been written is to depress the two keys 49 and 77 and allow the carriage to move leftward until it is 100 brought to position for printing the total on both the bill and the tally strip.

Various changes may be made without departing from the spirit of my invention. What I claim as new and desire to secure 110 by Letters Patent, is:—

1. In a typewriting machine and in tally strip mechanism, the combination of a platen, line spacing devices therefor, independent tally feeding devices, and means 115 operating automatically when the tally strip has arrived at the printing point for preventing the tally strip from being printed upon until after the tally feeding devices are operated.

2. In a typewriting machine and in tally strip mechanism, the combination of a traveling platen, line locking mechanism, and tally feeding means operative to feed the tally strip and also to unlock the line locking mechanism.

3. In a typewriting machine and in tally strip mechanism, the combination of a trav-

eling platen having a tally strip arranged at one end thereof, preventive means operative at a predetermined point to prevent printing operations of the machine, a key, and devices operative thereby to advance the tally strip and to render said preventive means inoperative.

4. In a typewriting machine and in tally strip mechanism, the combination of a platen, key controlled type bars, means for preventing said type bars from printing, and means for advancing the tally strip and simultaneously freeing said type bars to enable them to be actuated to print.

15. 5. In a typewriting machine and in tally strip mechanism, the combination of a platen having a tally strip arranged on it, line locking devices operative as the tally strip enters the printing field, and a key operative to advance the tally strip and also to unlock the line locking devices by a single operation.

6. In a typewriting machine and in tally strip mechanism, the combination of a traveling platen, printing instrumentalities, line spacing devices for the platen, means independent of said line spacing devices and of said platen for advancing a tally strip independently of the platen, means operative to prevent coöperation between the tally strip and the printing instrumentalities, and a single key operative to advance the tally strip and also operative on said preventive means to enable the tally strip to be printed upon when the printing instrumentalities are actuated.

7. In a typewriting machine and in tally strip mechanism, the combination of a platen; pawl and ratchet line feeding devices therefor, separate pawl and ratchet tally feeding devices, line locking mechanism, and a single key operative to unlock said line locking mechanism and to actuate said pawl and ratchet tally feeding devices.

8. In a typewriting machine and in tally strip mechanism, the combination of a platen, line spacing devices therefor, a line lock, a tally delivery roll, a tally receiving roll, pawl and ratchet mechanism connected to the receiving roll and separate from the platen line spacing devices, and a key operative on said pawl and ratchet mechanism to line feed the tally strip and simultaneously operative to unlock said line lock.

9. In a typewriting machine and in tally strip mechanism, the combination of a platen, coöoperative line locking stops, and tally feeding mechanism including a lever, said lever being operative to line feed the tally strip and to disconnect said line locking stops when they are in coöoperative engagement.

10. In a typewriting machine and in tally strip mechanism, the combination of a traveling platen, a line locking stop on the frame

of the machine, tally feeding devices including a pawl, a lever on which said pawl is mounted, and a coöoperative line locking stop also mounted on said lever, said lever being operative to actuate said pawl and to separate the coöperating line locking stops.

11. In a typewriting machine and in tally strip mechanism, the combination of a platen, a carriage on which the platen is mounted, a release key on the carriage, and tally strip feeding means operative by a key on the carriage, the tally strip feeding key being arranged in proximity to the release key and being operative concurrently therewith by the same hand which operates the release key.

12. In a typewriting machine and in tally strip mechanism, the combination of a platen, line spacing devices therefor, independent tally feeding devices, printing instrumentalities, and means for preventing the operation of the printing instrumentalities on the tally strip until after the tally strip feeding devices are operated.

13. In a typewriting machine and in tally strip mechanism, the combination of a traveling carriage, a platen thereon, a release key on the carriage, line locking devices, and a key for unlocking the same and for simultaneously advancing the tally strip in line spacing direction, said last named key being arranged in proximity to said release key.

14. In a typewriting machine and in tally strip mechanism, the combination of a traveling platen, printing instrumentalities, line spacing devices, means separate from said line spacing devices for advancing a tally strip independently of the platen, means to prevent the operation of the printing instrumentalities on the tally strip, and a single key operative to advance the tally strip and also to permit the printing instrumentalities to print upon the tally strip.

15. In a typewriting machine and in tally strip mechanism, the combination of printing types, a platen, line spacing devices therefor, independent tally feeding devices, means operating automatically when the tally strip is at the printing point to prevent the operation of the types, and means connected therewith and with the tally strip feeding devices to enable operation of the types only after operation of the tally strip feeding devices.

16. In a typewriting machine and in tally strip mechanism, the combination of printing types, a platen, print-preventing means operating when the tally strip arrives at the printing point, and means for spacing the tally strip and clearing the print-preventing means.

17. In a typewriting machine and in tally strip mechanism, the combination of a platen, printing mechanism, tally strip

mechanism, and tally strip feed devices connected to control the printing mechanism when the tally strip is at the printing point in such manner that the tally strip must be fed before the types can print upon it.

Signed at the borough of Manhattan, city of New York, in the county of New York,

and State of New York this 28th day of February A. D. 1912.
